US00D588062S

(12) **United States Design Patent**
Bao et al.

(10) **Patent No.:** **US D588,062 S**
(45) **Date of Patent:** **** Mar. 10, 2009**

(54) **SHELL OF THE VEHICLE AUXILIARY POWER GENERATION SYSTEM**

(75) Inventors: **Chengrong Bao**, Yancheng (CN); **Hongchun Ding**, Yancheng (CN); **Weifeng Chen**, Yancheng (CN); **Wenhai Xia**, Yancheng (CN); **Guangzhi Liu**, Yancheng (CN); **Shuguang Xie**, Yancheng (CN); **Yibo Shan**, Yancheng (CN); **Tianzhu Wang**, Yancheng (CN)

(73) Assignee: **Jiangsu Jianghuai Engine Co., Ltd.**, Yancheng (CN)

(**) Term: **14 Years**

(21) Appl. No.: **29/298,470**

(22) Filed: **Dec. 5, 2007**

(51) LOC (9) Cl. **13-01**

(52) U.S. Cl. **D13/122**; D15/28

(58) **Field of Classification Search** D13/122, D13/114, 110, 112, 184, 162; D15/5, 28, D15/17, 1, 10; D24/232; 180/89.1; 310/89
See application file for complete search history.

(57) **CLAIM**

The ornamental design for a shell of a vehicle auxiliary power generation system, as shown and described.

DESCRIPTION

FIG. 1 is a perspective view of a shell of a vehicle auxiliary power generation system of the present design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The rear view forms no part of the claimed design.
